PUNCH CARD-OPERATED SWITCH DEVICE
Rune H. I. Soderman, Stockton, N.J., Herbert L. Markman, Stockton, N.J. (P.O. Box 8503, Philadelphia, Pa.), and Abraham Markman, Stockton, N.J. (P.O. Box 8503, Philadelphia, Pa.); said Soderman assignor to Herbert L. Markman, Philadelphia, Pa.

Filed Sept. 26, 1962, Ser. No. 226,225
14 Claims. (Cl. 200—46)

This invention relates to electrical switch means, and it particularly relates to switch means set up in banks and actuated by punch cards to make or break electrical circuits for determining specified data.

Punch card actuated switch means heretofore generally in use have been difficult and expensive to produce and subject to easy breakdown, especially because of the fatigue and wear of various spring and spring-clip elements used therein. When repair was needed, it was generally a laborious and difficult task, even when only a single element had to be repaired or replaced.

It is one object of the present invention to overcome the above difficulties by providing a switch assembly which is easy and relatively inexpensive to produce and which can be easily repaired when such repairs are necessary.

Another object of the present invention is to provide a switch assembly of the aforesaid type which eliminates the use of springs, spring clips, and other such elements which are subject to early fatigue and easy breakdown.

Another object of the present invention is to provide a switch assembly of the aforesaid type which is highly efficient in its operation and easy to use.

Other objects and many of the attendant advantages of this invention will be readily appreciated as the same becomes better understood by reference to the following description when read in conjunction with the accompanying drawings wherein:

FIG. 1 is a front perspective view of an assembly embodying the present invention.

FIG. 2 is a fragmentary sectional view taken generally on line 2—2 of FIG. 1.

FIG. 3 is a somewhat enlarged, detailed view of a switch housing shown in FIG. 2.

FIG. 4 is a cross-sectional view taken on line 4—4 of FIG. 3.

FIG. 5 is a view similar to FIG. 4 but showing an alternative embodiment of the switch housing.

FIG. 6 is a fragmentary, front elevational view of a supporting panel for the switch housings made up of stacked blocks.

FIG. 7 is a fragmentary perspective exploded view of a form of the invention utilizing stacked blocks and showing a pair of blocks, in non-stacked position, together with a portion of an alternative form of plunger.

FIG. 8 is a view similar to FIG. 6 but showing an alternative embodiment of the stacked blocks.

FIG. 9 is a fragmentary top plan view of the upper surface of one of the stacked blocks in FIG. 8.

FIG. 10 is a fragmentary perspective view of the plunger used with the switch assembly illustrated in FIGS. 8 and 9.

FIG. 11 is a view similar to FIG. 9 but showing an alternative embodiment thereof.

FIG. 12 is a view similar to FIG. 10 but showing a plunger used with the switch assembly of FIG. 11.

Referring now in greater detail to the various figures of the drawings wherein similar reference characters refer to similar parts, there is shown a switch assembly, generally designated 10, comprising a base 12 having integral therewith a pair of spaced, vertical panels 14 and 16. The

2

panel 14 is provided with a series of rows of apertures through each of which extends the forward portion of a plunger 18. Each of these plungers 18 has a front end insertable into a corresponding aperture 20 in a front movable panel 22 while the rear portion of each plunger 18 extends through a corresponding aperture in a rear movable panel 24 and has a somewhat enlarged, cylindrical contact portion 26 at its rearmost end which is movable in a corresponding cylindrical switch housing 28 positioned in the panel 16.

The movable panels 22 and 24 are connected to each other for simultaneous movement by means of brackets 30. Guide pins 32 project forwardly from the fixed panel 14, adjacent each vertical edge thereof and these pins are received in corresponding apertures in the front portion of each bracket 30 to serve as guide means for maintaining the proper alignment of the movable panels during movement thereof along the upper surface of the base member 12. The panels 22 and 24 are movable by means of an actuating means comprising a finger 34 projecting forwardly from the central portion of the lower edge of the panel 22 and provided with an aperture to receive a pivot pin 36 connecting it to one end of a link 38. The opposite end of the link 38 is connected by a pivot pin 40 to one end of a lever 42 pivoted to the base at 44 and provided with an offset portion 46 having a handle 48.

The front movable panel 22 is provided with a vertical slot 50 centrally thereof, this slot 50 intersecting the apertures 29 (as best seen in FIG. 2), and adapted to hold a punch card 52 therein.

Each plunger 18 has a head 54 intermediate its ends, and this head bears against the rear movable panel 24 whereby when the plunger is moved rearwardly it moves the panel 24 along therewith, while when the panel 24 is moved forwardly it pushes the plunger ahead of it. The stationary panel 14 acts as a stop means to limit forward movement of the plunger by abutment with the head 54 (as illustrated in FIG. 2).

Each switch housing 28 comprises an outer cylindrical shell 56 constructed of electrically conductive material and mounted in an appropriate opening in the panel 16 which is, itself, constructed of electrically non-conductive material. On opposite front and rear faces of the panel 16 are respective plates 58 and 60, also made of electrically non-conductive material and having mating apertures to respectively receive the plunger 18 and the rear portion of the switch housing. These plates securely confine the switch housings in the panel 16.

The outer shell 56 of each switch housing is provided with an inwardly enlarged front end forming a front contact portion 60. Coaxial with the outer shell 56 and spaced inwardly therefrom by a cylindrical, electrically insulating intermediate shell 62 is an inner electrically conductive cylindrical shell 64. The front end of shell 64 is spaced from the enlarged front end 60 of shell 56 by an enlarged front portion 66 of intermediate shell 62. The three coaxial shells 56, 62 and 64, at their rear portions, are correspondingly reduced as they pass through plate 60, the shells 56 and 64 being connected at their rear ends to lead lines (not shown) connected to opposite sides of the circuit.

In the operation of the above-described device, a card 52 which has been punched in accordance with a specified code to provide particular data is placed in the slot 50 of the panel 22 and the handle 48 is then manipulated to move the panel 22 as well as the panel 24 rearwardly. If the card 52 has a hole in a position to receive a particular plunger 18, that plunger will remain stationary as the hole passes thereover and the contact portion 26 of the plunger will remain in engagement only with the front conductor 60 whereby that switch remains open. How-

ever, where the card 52 is not perforated, as it moves rearwardly, it pushes back the plunger to the position where the portion 26 bridges the insulated gap between the conductor portion 60 and the conductor shell 64 whereby the switch is closed. The number and position of the switches closed (or open as the case might be) determines the data obtained. After each use, the handle 48 is manipulated to move the plunger 18 forwardly with it until head 54 abuts panel 14 which limits its further forward movement. The punch card is then removed.

In FIG. 5 there is shown a modification of the switch housing of FIGS. 2, 3 and 4 wherein the housing 70 is rectangular instead of circular in cross-section and includes a rectangular outer shell 72 of insulating material and a rectangular inner shell 74 of insulating material. Upper and lower outer conductive plates 76 and 78 are positioned between the insulator shells 72 and 74 and upper and lower inner conductive plates 80 and 82 are positioned inwardly of insulative shell 74 and are spaced from each other by the inner shell. Otherwise, this modification is similar to that shown in FIG. 3 in that the outer plates 76 and 78 extend forwardly beyond the inner plates 80 and 82 and are provided with enlarged forward portions similar to those shown at 60, these enlarged portions being spaced from the ends of plates 80 and 82 by insulator portions similar to those shown at 66.

Although not specifically illustrated, the panel 16 is preferably built up of a series of vertically-stacked blocks made of electrically non-conductive material, each block having a bank of hemispherical recesses on opposite faces thereof which mate with similar recesses on the blocks above and below to form the switch housings, the coaxial conductive and non-conductive shells 56, 62 and 64 being either printed or otherwise affixed to the walls of the recesses so that when the upper and lower recesses mate a complete switch housing is formed. On the other hand, if desired, the coaxial shells can be inserted after the blocks have been assembled and the openings formed.

The stacked block type of arrangement is more specifically illustrated in FIGS. 6 and 7 where the panel, generally designated 90, is made up of a series of vertically stacked blocks 92 having generally hemispherical recesses 94 on one face thereof and similar recesses 96 on the other face. These recesses mate to form openings 98 and, in the particular embodiment of the invention illustrated in FIGS. 6 and 7, the upper recesses 94 are fully coated with a conductive surface 100 except for non-conductive edge portions 102 along each side, while the lower recesses 96 are uncoated with conductive material except for an arcuate band 104 adjacent the front edge and an elongated strip 106 extending rearwardly from the band 104. The band 104 is spaced at each end from the edges of the recess 96 and the strip 106 is also spaced from the corresponding edge of the recess so that non-conductive side edges 108 are formed similar to edges 102. When the blocks are stacked upon each other, the edges 102 and 108 keep the conductive portions from touching. At the front end of each opening forming a switch housing, except for the edges 102 and 108, the band 104 and coating 100 form a complete conductive aperture. However, stretching rearwardly from the area of the band 104, the entire upper portion of the opening is non-conductive except for the strip 106. The coating 100 and strip 106 are connected by lead wires (not shown) to opposite sides of the circuit.

Coating with each switch housing formed by the openings 98 is a plunger 110 shaped similarly to plungers 18 except that it is hollow and is made of a flexible or resilient electrically non-conductive material. Adjacent the rear end of the plunger 110 is an arcuate band 112 of electrically conductive material. This band extends only partly around the plunger, leaving a gap which, when the plunger is inserted into the opening 98, mates with the conductive strip 106.

In the operation of the switch mechanism of FIGS. 6

and 7, when the plunger is in the forward position, the band 112 connects the band 104 with the conductive coating 100 and the circuit is closed. However, when the plunger is pushed back, the band 112 is in contact only with the non-conductive portion of recess 96 while the gap in the band 112 mates with the strip 106, thereby opening the circuit. The resilient nature of the plunger 110 and its hollow construction gives it a flexibility which causes it to retain a tight frictional contact with the walls of the opening 98 throughout its movement forward and backward therein.

In FIG. 8, a modification of the invention is shown wherein the panel 120, similar to panel 90, is built up of blocks 122 which are similar to blocks 92 except for the fact that only the undersurface of the blocks 122 are provided with generally hemispherical recesses 124, the upper surfaces being flat. With this construction, the plungers are of corresponding hemispherical shape. Although this type of block construction can be alternatively used both with the form of the invention shown in FIGS. 1 to 5 and that shown in FIGS. 6 and 7, it is illustrated as being used with a form of the invention illustrated in FIGS. 9 and 10 wherein two spaced, parallel electrically conductive strips 126 and 128 are provided on the flat upper surface of each block bounded by each convex recess 124 of the block above. The strip 126 is provided with a gap 130 close to its front end while the strip 128 is made integral with a bridging strip 132 at the front end. The bridging strip 132 is also integral with the front end of strip 126 forwardly of the gap 130. The rear ends of the strips 126 and 128 are connected to opposite sides of the circuit by lead lines (not shown).

The plunger 134 (shown in FIG. 10) utilized with the construction of FIGS. 8 and 9 comprises an electrically non-conductive body of hemispherical cross-section with the top surface being flat; at the front end of the flat top surface is an electrically conductive plate 136, this plate being positioned adjacent one edge of the plunger. When the plunger 134 is inserted in the opening formed by recess 124, it is reversed from the position shown in FIG. 10 so that the flat side is down in abutment with the conductive strips 126 and 128 in FIG. 9 and the plate 136 is at the front. When the plunger is in the forward position, the conductive plate 136 of the plunger is in contact with the gap 130 and the gap is bridged to close the circuit. As the plunger is pushed back, the plate 136 leaves the gap 130 and the circuit is opened.

In FIGS. 11 and 12, the construction is almost identical with that of FIGS. 9 and 10 except that the two parallel, spaced conductive strips 140 and 142 both extend from one end to the other and both are provided with transverse portions, as at 144 and 146 respectively, at the front end. A gap 148 separates the portions 144 and 146. The plunger 150 used in conjunction with this form of the device is identical to plunger 134 except that the conductive plate 152 is in the center of the front edge of the flat top surface so that when the plunger is in the forward position the plate 152 bridges the gap 148 and closes the circuit, while when the plunger is pushed back, the plate 152 leaves the gap 148 and the circuit is opened.

In the forms shown in FIGS. 8 to 12, the gaps 130 and 148 and the plates 136 and 152 are shown at the forward ends of their respective structural units, however, they can equally as well be placed rearwardly so that the circuit is open when the plunger is forward and closed as it moves rearwardly.

Obviously many modifications and variations of the present invention are possible in the light of the above teachings. It is, therefore, to be understood that within the scope of the appended claims, the invention may be practiced otherwise than as specifically described.

The invention which is claimed is:

1. A punch card-operated switch assembly comprising a base member, a switch housing support panel rigidly

connected to said base member, a plurality of individual switch housings in a bank, said housings opening from a front face of said support panel, each switch housing having a pair of contact members of which one contact member is connected to one side and the other is connected to an opposite side of an electrical data circuit, an individual switch plunger axially movable in each switch housing, a pair of spaced, parallel movable panels movable in unison toward and away from said front face of the support panel, a first one of said movable panels being positioned between the second of said movable panels and the support panel, said second movable panel having a slot therein for removably receiving and holding a punch card, said slot being transverse to the plane of movement of said plungers, said second panel having a plurality of apertures therethrough corresponding in number and positions to said switch housings in said support panel, each aperture intersecting said slot and being constructed to slidably receive a corresponding plunger, said apertures permitting relative movement between said second movable panel and said individual plungers when any aperture in a punch card positioned in said slot mates with a plunger while, when said punch card has no mating aperture, movement of said second movable panel toward said support panel causes abutment of the plunger with the card and movement of the plunger in conjunction with the movable panels, means on said first movable panel engaging with said plungers to move said plungers away from said support panel upon movement of said first movable panel in the corresponding direction, the contact members in each switch housing being spaced from each other to form an electrical gap, and the corresponding plunger having an electrical contact constructed and arranged to bridge said gap when said plunger is in one position of axial movement and to leave said gap unbridged in other axial positions of said plunger.

2. The switch assembly of claim 1 wherein said support panel is constructed of a series of vertically stacked blocks of electrically non-conductive material, each block having a plurality of recesses on at least one side thereof, said recesses forming enclosures encompassing the switch housings.

3. The switch assembly of claim 1 wherein each switch housing comprises coaxially arranged inner and outer tubular conductive sleeves of electrically conductive material forming said pair of contact members, the conductive sleeves being radially spaced from each other by an electrically non-conductive intermediate sleeve and the conductive sleeves having contact portions at corresponding ends, said contact portions being axially spaced from each other to form said electrical gap.

4. The switch assembly of claim 1 wherein each switch housing comprises an inner and outer casing of electrically non-conductive material, a first pair of oppositely-disposed conductive plates between the inner and outer casings and a second pair of oppositely-disposed conductive plates inwardly of the inner casing, the first pair of plates being electrically connected in common to the circuit and the second pair of plates being electrically connected in common to the circuit, said first pair of plates having contact portions and said second pair of plates having contact portions, the contact portions of said first pair of plates being spaced from the contact portions of said second pair of plates axially 65 of the movement of said plunger.

5. The switch assembly of claim 1 wherein each switch housing comprises upper and lower curved walls of non-conductive material, one of said walls being coated over its entire surface with an electrically conductive material except for its opposite longitudinal edges mating with the corresponding edges of the other wall, said edges being non-conductive, and the other wall having an arcuate electrically conductive band thereon at one end and an electrically conductive strip extending from said band to

5 the opposite end of the corresponding wall, and the plunger for each switch housing being cylindrical and having an arcuate band partially encompassing the circumference at one end thereof, said last-mentioned arcuate band having spaced ends leaving a gap which mates with the conductive strip on said other wall during movement of the plunger in the switch housing.

10 6. The switch assembly of claim 1 wherein the pair of contact members comprise a pair of spaced, parallel electrically conductive strips extending longitudinally of the path of movement of the plunger, at least one of said strips having a transverse portion extending toward the other strip and a gap between said transverse portion and the other strip, and the plunger being electrically non-conductive but having an electrically conductive contact plate positioned to bridge said gap when said plunger is in a predetermined position.

7. The switch assembly of claim 1 wherein said plungers are constructed of resilient material.

8. A punch card-operated switch assembly comprising a single panel of electrically non-conductive material, a bank of electrical switch housings in said panel, a plunger movable in each of said switch housings, each switch housing including a pair of electrical conductors spaced from each other in the direction of movement of the corresponding plunger, each plunger having an electrical contact thereon arranged to open and close an electrical circuit between said spaced electrical conductors upon movement of said plunger from one position to another, a punch card holder movable toward and away from said support and having apertures therein to correspond in number and position with said switch housings and plungers, said holder being constructed to hold a punch card so that any perforations in the card mate with corresponding apertures in said holder, punched portions of said card permitting penetration therethrough of corresponding plungers when said holder is moved toward said support and unpunched portions acting to push the corresponding plungers in the direction of movement of the holder when the holder is moved toward said support, and means rigidly connected to said holder to move said plungers away from said support as said holder is moved away from said support.

45 9. In a punch card-operated switch assembly, a switch means comprising a housing having a pair of contact members of which one contact member is connected to one side and the other is connected to an opposite side of an electrical data circuit, a plunger axially movable in said housing, the contact members being laterally spaced from each other and extending longitudinally of the direction of movement of said plunger from one common end plane to an opposite common end plane, one of said contact members having a portion spaced axially from a corresponding portion of the other contact member to form an electrical gap, and the plunger having an electrical contact constructed to bridge said gap when said plunger is in one position of axial movement and to leave said gap unbridged in other axial positions of said plunger.

50 10. The assembly of claim 9 wherein the switch housing comprises coaxially arranged inner and outer tubular conductive sleeves of electrically conductive material forming said pair of contact members, the conductive sleeves being radially spaced from each other by an electrically non-conductive intermediate sleeve and the conductive sleeves having contact portions at corresponding ends, said contact portions being axially spaced from each other to form said electrical gap.

70 11. The assembly of claim 9 wherein the housing comprises an inner and outer casing of electrically non-conductive material, a first pair of oppositely-disposed conductive plates between the inner and outer casings and a second pair of oppositely-disposed conductive plates inwardly of the inner casing, the first pair of plates being electrically connected in common to the circuit and the

second pair of plates being electrically connected in common to the circuit, said first pair of plates having contact portions and said second pair of plates having contact portions, the contact portions of said first pair of plates being spaced from the contact portions of said second pair of plates axially of the movement of said plunger.

12. The assembly of claim 9 wherein the housing comprises upper and lower curved walls of non-conductive material, one of said walls being coated over its entire surface with an electrically conductive material except for its opposite longitudinal edges mating with the corresponding edges of the other wall, said edges being non-conductive, and the other wall having an arcuate electrically conductive band thereon at one end and an electrically conductive strip extending from said band to the opposite end of the corresponding wall, and the plunger for each switch housing being cylindrical and having an arcuate band partially encompassing the circumference at one end thereof, said last-mentioned arcuate band having spaced ends leaving a gap which mates with the conductive strip on said other wall during movement of the plunger in the switch housing.

13. The assembly of claim 9 wherein the housing comprises upper and lower curved walls of non-conductive material, one of said walls being coated over its entire surface with an electrically conductive material except for its opposite longitudinal edges mating with the corresponding edges of the other wall, said edges being non-conductive, and the other wall having an arcuate electrically conductive band thereon at one end and an electrically conductive strip extending from said band to the opposite end of the corresponding wall, and the plunger for each switch housing being cylindrical and having an arcuate band partially encompassing the circumference at one end thereof, said last-mentioned arcuate band having spaced ends leaving a gap which mates with the conductive strip on said other wall during movement of the plunger in the switch housing.

14. The assembly of claim 9 wherein the housing comprises upper and lower curved walls of non-conductive material, one of said walls being coated over its entire surface with an electrically conductive material except for its opposite longitudinal edges mating with the corresponding edges of the other wall, said edges being non-conductive, and the other wall having an arcuate electrically conductive band thereon at one end and an electrically conductive strip extending from said band to the opposite end of the corresponding wall, and the plunger for each switch housing being cylindrical and having an arcuate band partially encompassing the circumference at one end thereof, said last-mentioned arcuate band having spaced ends leaving a gap which mates with the conductive strip on said other wall during movement of the plunger in the switch housing.

15. The assembly of claim 9 wherein the housing comprises upper and lower curved walls of non-conductive material, one of said walls being coated over its entire surface with an electrically conductive material except for its opposite longitudinal edges mating with the corresponding edges of the other wall, said edges being non-conductive, and the other wall having an arcuate electrically conductive band thereon at one end and an electrically conductive strip extending from said band to the opposite end of the corresponding wall, and the plunger for each switch housing being cylindrical and having an arcuate band partially encompassing the circumference at one end thereof, said last-mentioned arcuate band having spaced ends leaving a gap which mates with the conductive strip on said other wall during movement of the plunger in the switch housing.

16. The assembly of claim 9 wherein the housing comprises upper and lower curved walls of non-conductive material, one of said walls being coated over its entire surface with an electrically conductive material except for its opposite longitudinal edges mating with the corresponding edges of the other wall, said edges being non-conductive, and the other wall having an arcuate electrically conductive band thereon at one end and an electrically conductive strip extending from said band to the opposite end of the corresponding wall, and the plunger for each switch housing being cylindrical and having an arcuate band partially encompassing the circumference at one end thereof, said last-mentioned arcuate band having spaced ends leaving a gap which mates with the conductive strip on said other wall during movement of the plunger in the switch housing.

13. The assembly of claim 9 wherein the pair of contact members comprise a pair of spaced, parallel electrically conductive strips extending longitudinally of the path of movement of the plunger, at least one of said strips having a transverse portion extending toward the other strip and a gap between said transverse portion and the other strip, and the plunger being electrically non-conductive but having an electrically conductive contact plate positioned to bridge said gap when said plunger is in a predetermined position.

14. The assembly of claim 9 wherein the plunger is constructed of resilient material.
